US0D1032365S

(12) **United States Design Patent** (10) Patent No.: **US D1,032,365 S**
 Sill et al. (45) Date of Patent: ** Jun. 25, 2024

(54) **COMPARTMENTED CARTON INSERT**(71) Applicant: **Inno-Pak, LLC**, Delaware, OH (US)(72) Inventors: **Jonathan D. Sill**, Delaware, OH (US);
Steven A. Mayer, Indianapolis, IN (US)(73) Assignee: **Inno-Pak, LLC**, Delaware, OH (US)(***) Term: **15 Years**(21) Appl. No.: **29/904,870**(22) Filed: **Oct. 12, 2023**

CLAIM

The ornamental design for a compartmented carton insert, as shown and described.

DESCRIPTION

FIG. 1 is a perspective view of a compartmented carton insert showing our new design;
 FIG. 2 is a front view thereof;

FIG. 3 is a rear view thereof;
 FIG. 4 is a left side view thereof;
 FIG. 5 is a right side view thereof;
 FIG. 6 is a top plan view thereof;
 FIG. 7 is a bottom plan view thereof;
 FIG. 8 is another perspective view thereof showing the compartmented carton insert in use with an exemplary carton;
 FIG. 9 is a perspective view of a second embodiment of a compartmented carton insert, showing our new design;
 FIG. 10 is a front view thereof;
 FIG. 11 is a rear view thereof;
 FIG. 12 is a left side view thereof;
 FIG. 13 is a right side view thereof;
 FIG. 14 is a top plan view thereof;
 FIG. 15 is a bottom plan view thereof;
 FIG. 16 is another perspective view thereof showing the compartmented carton insert in use with an exemplary carton;
 FIG. 17 is a perspective view of a third embodiment of a compartmented carton insert, showing our new design;
 FIG. 18 is a front view thereof;
 FIG. 19 is a rear view thereof;
 FIG. 20 is a left side view thereof;
 FIG. 21 is a right side view thereof;
 FIG. 22 is a top plan view thereof;
 FIG. 23 is a bottom plan view thereof;
 FIG. 24 is another perspective view thereof showing the compartmented carton insert in use with an exemplary carton;
 FIG. 25 is a perspective view of a fourth embodiment of a compartmented carton insert, showing our new design;
 FIG. 26 is a front view thereof;
 FIG. 27 is a rear view thereof;
 FIG. 28 is a left side view thereof;
 FIG. 29 is a right side view thereof;
 FIG. 30 is a top plan view thereof;
 FIG. 31 is a bottom plan view thereof; and,
 FIG. 32 is another perspective view thereof showing the compartmented carton insert in use with an exemplary carton.

The dash-dash broken lines are shown for the purpose of illustrating environmental subject matter of an exemplary carton and form no part of the claimed design.
